RAZOR RACK

Charles E. Dunham, Los Angeles, Calif.

Application July 22, 1944, Serial No. 546,130

5 Claims. (Cl. 248—300)

My invention relates to suspending means for articles having a handle and a plate-like head portion arranged across the top of the handle projecting to one or both sides of the handle and having a down-turned lip along the edge of the top.

The invention particularly relates to suspending means for articles such as safety razors of the "Gillette" type. As is well known, safety razors are generally laid down upon a shelf or other flat surface after use, and as they often are not dried after shaving, are apt to soil the surface on which they are laid. Further, because of its shape, the razor is liable to be knocked off the surface on which it is placed, for instance, by becoming accidentally caught by other articles being removed from the shelf.

It is an object of my invention to provide a suspending means or support for articles of the kind described which may be readily hung upon a nail or hook in a wall and, though simple and inexpensive to produce, is effective and convenient in use.

A further object of the invention is to provide a support or bracket for a safety razor of the "Gillette" type which can be folded flat and included with the package in which the razor is sold.

Another object of the invention is to provide a support or bracket for a safety razor, formed as a single unit having no separable parts and therefore not subject to deterioration caused by wearing out of parts.

Further features and objects of the invention will hereinafter appear from the following description and accompanying drawing, in which a preferred form of the invention is illustrated by way of example. It is to be understood, however, that the scope of my invention is not in any way limited by this illustrative showing but only as defined by the appended claims.

In the drawing:

Fig. 1 is a perspective view of the razor support affixed to a wall,

Fig. 2 is a view in side elevation of the support showing the contour thereof before placing a razor thereon, and

Fig. 3 is a view similar to that of Fig. 2, but showing a razor hung on the support.

Referring now to Fig. 1, the numeral 10 indicates a forward wall, and the numerals 12 and 14 the front and back portions, respectively, of the top section of the support. It will be noted that a crease 13 acting as a hinge separates the

front and back portions of the top section of the support for a purpose to be later described.

The back, or section of the support intended to be placed against a wall or other vertical surface on which the support may be hung, is indicated at 22. A bottom leaf 18 inturned from the front wall 10 and a bottom leaf 16 turned forwardly from the back section 22 are laid one upon the other and secured together in any suitable manner as for instance by glueing together preferably with an adhesive of a waterproof and permanent type. It will be seen that the support described forms a unitary open sided box-like structure except that because of the crease 13 in the top side and the configuration given to the top, the width of the top may be slightly less than the bottom section of the support formed by the overlapping leaves 16 and 18.

The configuration given to the top of the support is such that the front or outer portion 12 of the top is inclined upwardly from the crease 13 to the upper outer edge of the box, this configuration being obtained by moving the front wall of the support upwardly with respect to the back wall 22, the back portion 14 of the top being caused to remain substantially perpendicular to the back section 22, thus also causing the bottom section to incline upwardly from back to front.

30 The support may be hung upon a wall with adhesive or by thumb tacks 24 pressed through the back 22 into the wall, or hung on a nail or nails engaging suitably shaped apertures in the back.

35 Referring now to Fig. 3, it will be seen that a razor of the "Gillette" type indicated generally by the numeral 26 comprises a handle 30 and a curved rectangular plate-like head 32. The head comprises a guard section 28 which is somewhat wider than the blade 34 and is turned downwardly toward the handle along and outwardly of the edge of the blade. Crease 13 is so arranged along the top of the support that the front part 12 of the top will be engaged by the down-turned edge of the guard section 28 when the razor is placed upon the support, with the handle 30 laying against the front wall 10 of the support. Since both edges of the razor are equidistant from the handle, it is immaterial which edge is engaged 40 with the top of the support. The support may be made of a single thickness of suitable material, such as cardboard, preferably treated to render it water resistant.

45 The effect of placing the razor in the position described is to increase the angularity of the

front portion 12 with respect to the back portion 13 of the top of the support since the creased single thickness top will fold readily about the crease 13 while the double thickness bottom of the support resists buckling. Since any downward movement of the front wall due to the weight of the razor causes the bottom section of the support to assume a more nearly perpendicular position with respect to the back wall of the support, the lower end of the handle is pushed outwardly, resulting in more firmly seating the edge of the razor guard in the crease at the base of the inclined front or outer part 12 of the top.

While I have described a preferred form of my invention, it will be apparent that various modifications in the arrangement of the suspending means or bracket and changes in the configuration thereof may be effected without departing from the scope of the invention as defined in the appended claims.

I claim:

1. A support for articles having a handle secured to the under face of a plate-like head having a straight downwardly turned edge which edge is spaced from the handle, comprising: a top section adapted to be mounted on a wall or other vertical surface, said top section having a front portion and a back portion hingedly connected along a line extending substantially parallel to and spaced from the front edge of the top section sufficiently to insure that the down-turned edge of the head of the article to be supported engages against the said front portion; and a front wall extending downwardly from and connected to the front edge of the top section and mounted upon said wall in spaced relation to the line of support on the wall of said top section.

2. A support for articles having a handle secured to the under face of a plate-like head having a straight downwardly turned edge which edge is spaced from the handle comprising: a top section adapted to be mounted on a wall or other vertical surface, said top section having a front portion and a back portion hingedly connected along a line extending substantially parallel to and spaced from the front edge of the top sufficiently to insure that the downturned edge of the head of the article to be supported engages against the said front portion; a front wall connected to the front edge of the top and extending downwardly; a bottom wall connected to the bottom of the front wall and extending toward and abutting against the wall upon which

said support is mounted, said bottom wall being held against said wall in spaced relation to said top section and acting to maintain said front wall in substantially vertical position.

3. A support for articles having a handle secured to the under face of a plate-like head having a straight downwardly turned edge which edge is spaced from the handle, comprising: a top section adapted to be mounted on a wall or other vertical surface, said top section providing an inclined portion adapted to engage below and support said edge of said head; a front wall connected to the front edge of the top and extending downwardly; a bottom wall connected to the bottom of the front wall and sloped downwardly and rearwardly from said connection with the front wall; and a back wall extending from the rear edge of the bottom wall to the rear edge of the top section, said back wall being adapted to be secured to a wall or other substantially vertical surface upon which said support is mounted.

4. A wall support for safety razors of the kind having a rectangular plate-like head extending across a handle portion and having a straight downwardly turned edge, comprising: a piece of material shaped to provide an open-sided box-like structure having a top surface providing an inclined portion adapted to engage below and support an edge of the head of the razor; a front wall adapted to engage against the handle of the razor; a bottom portion inclined downwardly and backwardly from the lower edge of said front portion; and a back portion connecting the back of the bottom portion to the rear edge of the top portion and adapted to be supported upon a wall or other substantially vertical surface.

5. A wall support for safety razors of the kind having a rectangular plate-like head extending across a handle portion and having a straight downwardly turned edge, comprising: a piece of material shaped to provide an open-sided box-like structure having a top surface providing a support for said razor head along said downwardly turned edge thereof; a front wall adapted to engage against the handle of the razor; a bottom portion inclined downwardly and backwardly from the lower edge of said front portion; and a back portion connecting the back of the bottom portion to the rear edge of the top portion and adapted to be supported upon a wall or other substantially vertical surface.
